UNITED STATES PATENT OFFICE.

MEYER RAPHAEL, OF PORTLAND, OREGON.

REGISTERING-TAG.

SPECIFICATION forming part of Letter's Patent No. 366,253, dated July 12, 1887.

Application filed November 12, 1886. Serial No. 213,716. (No model.)

To all whom it may concern:

Be it known that I, MEYER RAPHAEL, a citizen of the United States, residing at Portland, in the county of Multnomah and State of Oregon, have invented certain new and useful Improvements in Registering-Tags, of which the following is a specification, reference being had therein to the accompanying drawings, in which—

- 10 Figure 1 represents a plan view of a tag constructed according to my improvement. Fig. 2 is a central vertical section of the same. This improvement relates to a tag designed to be used with bolts or rolls of cloth, and provided with a registering device for keeping an account of the number of yards or quantity of cloth or other material sold off the same, whereby it may be readily seen how much material is left unsold; and the invention consists in 15 20 the peculiar combinations and construction and arrangement of parts, hereinafter more fully described, and then definitely pointed out in the claims.

I will now describe one plan of carrying out 25 my invention by referring to the accompanying drawings, in which—

A represents a plate, formed preferably of metal or of compressed card-board, having a countersunk or depressed portion at *a*, in the 30 center of which is pivoted a wheel or disk, B, having several (preferably six) teeth, *b*, and a series of numerals—viz., 1, 2, 3, 4, 5, and 0, if six teeth are formed on the disk. Above the plate A and disk B is a plate, C, secured 35 fast to the plate A and covering the major part of said disk B, but having an aperture, *c*, in its face, through which one of the numerals on said disk B may be seen. Pivoted to the center of the plates A and C is a pointer, D, 40 having a stud or pin, *d*, projecting from both sides of the same, the lower end of which stud works in a groove, *a'*, formed in the plate A. At E is shown a protecting-plate, which may not be necessary when the plate A is formed 45 of metal; but if of paper or card-board the said plate E will be found to be very useful in protecting the plate A from breaking. The extreme end of the pointer passes under the plate E, and it is thus prevented from bending 50 upward and from catching the cloth. Around the plate A, or on the plate E, as desired, I

print, stamp, engrave, or otherwise mark a series of figures, from 1 to 10, to indicate yards, and between each figure I make three lines to indicate the division of a yard. In the plate C, 55 I prefer to make a curved or semicircular opening, *c'*, through which will show a portion of the plate A, and around the edge of said opening I engrave, stamp, print, or otherwise mark the following: "Lot, Yds., Cost, Price." If 60 the plate A is made of paper or card-board, the number of the lot and the yards in the piece and the cost and selling prices may be written on the same opposite the appropriate words around the semicircular opening. If, 65 however, the plate A be made of metal, a strip of paper may be inserted in the slot or opening *c'*, on which the figures may be written, and which may be secured there by cementing, or in any convenient way. 70

I design to use this tag in the following manner: When a piece of cloth is received, the number of the lot, the number of yards it contains, and its cost and selling prices are marked on the semicircular space, and the tag 75 is then inserted between the folds of the cloth. When a portion is sold, the clerk who cuts it off turns the pointer to the right until it is opposite the line or figure indicating the quantity sold. If more than ten yards—say twelve—80 is sold, the pin *d*, as it passes around in the groove *a'*, comes in contact with one of the arms *b* of the disk B, and thus shows the figure "1," which means "10," and the pointer is left at the figure 2, which, added to the ten, makes 85 12. If another lot—say of eleven yards—is sold, the pointer is carried around again until the disk B is again moved so as to show the figure 2 thereon, and the pointer is left at the figure 3, which, added to the 20 represented 90 by the figure 2 on the disk, makes 23, showing that twenty-three yards have been sold. By subtracting this number from the number of yards noted on the semicircular space it will be at once seen how much remains unsold; or the 95 register may be used another way. When the goods are received, the register is set at the number of yards the roll contains, and then as the pointer is moved to indicate the number of yards sold the figures at which it is left will 100 show how much remains on the roll unsold. In this case, however, the pointer must be

turned in the reverse direction, or the figures on the register must be made the reverse way from that shown. It will thus be seen that I have produced an article that will be very 5 convenient to store-keepers and others, as by its use the number of yards sold and cut off from any piece of goods can be easily registered and the number of yards remaining in the piece ascertained at once, thus keeping a 10 merchant or his clerks posted as to the quantity of goods every piece contains without having to measure the same while waiting on the customer, and, moreover, it will save the tedious job of measuring every piece of goods 15 when taking stock. In some cases I may make an opening in the back of the plate A, as shown by dotted lines in Fig. 1, and slip a thin piece of card-board between the two plates. Where more than fifty yards are in a piece, I may use 20 a larger registering-disk—such as is shown in dotted lines in the upper part of Fig. 1—which may be numbered from 1 to 0, in which case I may dispense with the small disk; or I may provide said small disk with one tooth longer 25 than the others, as shown at *x*, which may operate on the large wheel at every revolution. It is of course evident that any reasonable number of figures or divisions may be made on the plates or disks to suit the varying circumstances of the case. I wish it to be understood that it makes no difference where the 30 figures are placed, whether on the plates A or E, or even on the plate C; but I prefer them made on the plate E. So far, however, as the 35 effect produced is concerned, it makes no difference, and in either of the places named I should consider them as equivalent for the arrangement shown, as in each place the plate A would be provided with the figures, whether

they are made directly on said plate A or are 40 made in a separate piece attached thereto.

What I claim as new is—

1. In a merchandise-tag, the combination, with the plate A and toothed disk B, each provided with suitable numbers, of the pivoted 45 pointer D, provided with the pin *d*, for operating on the teeth of the disk, substantially as described.

2. In a merchandise-tag, the combination, with the plate A and toothed disk B, each 50 provided with suitable numbers, of the plate C, partially covering the disk B, and the pivoted pointer D, provided with pin *d*, substantially as described.

3. In a merchandise-tag, the combination, 55 with the plate A and toothed disk B, each provided with suitable numbers, of the plate C, partially covering the disk B and having an opening to allow of the marking of the number of yards, &c., and the pivoted pointer 60 D, working over said plate C and provided with a pin, *d*, to operate the disk B, substantially as described.

4. In a merchandise-tag, the combination, with the plate A and toothed disk B, each 65 provided with suitable numbers, of the protecting-plate E and the pointer D, having a pin for operating the disk B, and its point passing under the protecting-plate, substantially as described.

In testimony whereof I affix my signature, in presence of two witnesses, this 6th day of October, 1886.

MEYER RAPHAEL.
